CLAIM

The ornamental design for a table saw with telescoping rails, as shown and described.

DESCRIPTION

FIG. 1 is a front elevational view of a table saw with telescoping rails showing our new design.

FIG. 2 is a right side elevational of the table saw.

FIG. 3 is a rear elevational of the table saw.

FIG. 4 is a left side elevational of the table saw.

FIG. 5 is a front perspective view from the left side of the table saw.

FIG. 6 is a rear perspective view from the right side of the table saw.

FIG. 7 is a top plan view of the table saw; and,

FIG. 8 is a top plan view of the table saw with the telescoping rails extended.

In the above drawing, any broken line illustration is not part of the design sought to be patented. In addition, any views not shown thereof do not form a part of the invention.
